UNITED STATES PATENT OFFICE

2,426,670

APPARATUS FOR CONNECTING METALLIC STRIPS

David N. Cooley, Gary, Ind.

Application December 19, 1945, Serial No. 635,929

3 Claims. (Cl. 164—109)

1

This invention relates to an improved manner of connecting metallic strips together for continuous pickling or annealing and more particularly to the punch and die used for stamping out the interconnecting tongue or stitch portions.

The generally accepted method of joining the ends of strip metal so that it can be continuously annealed, pickled or treated is to overlap the two ends and cut a plurality of coincidental tongues through the superposed strips, relatively move the two superposed strips lengthwise and then bend the tongues downwardly so that the lower tongue engages the upper strip and the upper tongue engages the lower tongue. The punches and dies heretofore used for striking out the tongues or stitches became dull very quickly causing the metal to tear or rupture, thereby preventing the relative shifting of the sheets prior to bending the tongues down. Moreover, the use of such punches and dies has been limited to one thickness of sheet metal. While attempts have been made to compensate for this and permit their use on a variety of thicknesses by increasing or decreasing the stroke of the punch, there is a tendency to tear the metal at the base of the tongue and cause failure of the connection.

It is accordingly an object of the present invention to provide a stitching apparatus that is simple and dependable in use.

It is another object to provide a stitching apparatus that will accommodate a wide variety of thicknesses without adjustment of the parts thereof.

It is a further object to prevent sticking together of the metal strips after being punched, so they can be easily shifted relative to each other prior to bending the tongues down to lock the strips together.

The foregoing and further objects will be apparent from the specification and drawing, wherein:

Figure 1 is a plan view of a die;

Figure 2 is an isometric view of a punch;

Figure 3 is a sectional elevation showing the die and punch with superposed thin sheets therebetween in position of stitching;

Figure 4 is a similar view showing the punch at the upper end of the punching stroke;

Figure 5 is a view similar to Figure 4, but showing materially thicker superposed sheets;

Figure 6 is a partial section of the rolls for bending down the struck out tongues to lock the sheets together; and

Figure 7 is a plan view of the struck out tongues after being bent down by the rolls of Figure 6.

2

A plurality of spaced die members 2 are contained in a suitable frame and extend across the width of the superposed ends S and S' of sheet material to be stitched together. Directly beneath the die members 2 are a plurality of punches 4 adapted to be simultaneously operated by suitable cranks or cams (not shown).

The die openings 2a and the punches 4 are generally rectangular in shape with one side in the form of an outwardly extending triangle. Such shape will hereinafter be referred to as a rectangular polygon. The sides 6 and the sloping sides 8 of the die and the corresponding sides 10 and 12 of the punch are sharp and adapted to cut metal strip received therebetween to cut out the stitches or tongues. The heel portion 14 of the die and the corresponding portion 16 of the punch are rounded off so that metal compressed therebetween will not be cut.

10 In accordance with the teachings of the present invention, the sides 10 of the punch are somewhat shorter than the sides 6 of the die. Thus when the punch is inserted in the die, the full extent of its stroke as indicated by the point 28,

15 with the edges 12 of the punch in close proximity to the edges 8 of the die, a space 24 is provided between the rounded off heel 14 of the die and the heel 16 of the punch. This space 24 should be about equal to the combined thick-

20 nesses of the thickest sheets to be stitched thereby. It is noted that the point 28 is always the same since the stroke of the punch need not be changed in order to accommodate various gauge sheets. At the point of maximum separation, a

25 space 20 is provided between the die and punch, which is equal to the thickness of the thickest sheets to be punched plus the stroke of the punch. This permits a wide range of sheet gauges to be stitched without changing or adjusting the stroke

30 of the punch. Figure 4 shows the punching operation on thin gauge sheets S, S', and Figure 5 shows the operation on thicker gauge sheets S². It is understood that sheets of heavier gauge

35 whose combined thickness does not exceed the distance 24 between the die and the punch may be punched therebetween. The sheets may tear slightly adjacent the rear edges of the tongues 22 but, due to the sides 10 and 6 of the punch and die being substantially square, the tear, if any, will likewise be straight and therefore not detrimental.

40 After the sheets have been punched, one of them is moved a slight distance longitudinally relative to the other and the tongues 22 are bent

down by pinch rolls 30 to securely lock the sheets together, as shown in Figures 6 and 7.

While I have shown and described one specific embodiment of my invention, it will be understood that this embodiment is merely for the purpose of illustration and description and that various other forms may be devised within the scope of my invention, as defined in the appended claims.

I claim:

1. Apparatus for connecting metallic sheets including a profiled die and punch, said die and punch being provided with heel clearance, said clearance when the punch is at the outer limit of its stroke being equal to the combined thickness of the thickest sheets to be punched therebetween plus the stroke of the punch.

2. Apparatus for connecting metallic sheets including a die and punch having a rectangular polygonal profile, said die and punch being provided with heel clearance, said heel clearance when the punch is at the outer limit of its stroke being equal to the combined thickness of the thickest sheets to be punched therebetween plus the stroke of the punch.

3. Apparatus for punching tabs in a pair of superposed metallic sheets prior to relatively moving the punched sheets lengthwise and then rolling down the tabs to lock the sheets together comprising a die and a reciprocable punch, said punch and die having cutting surfaces at the

sides and ends thereof and non-cutting heel surfaces, the sides of said die and punch being slightly flared outwardly from the heel surfaces and the heel surfaces being substantially normal to the longitudinal centerline of superposed sheets to be punched by the die and punch, the clearance between the heel portions of said die and punch when the punch is at the outer limit of its travel being equal to the combined thickness of the thickest pair of sheets to be punched plus the length of travel of said punch and when said punch is at the inner limit of its travel said clearance being equal to the combined thickness of the thickest pair of sheets to be punched therebetween.
